UNITED STATES PATENT OFFICE.

JOHN M. SINER, OF PARISH, FLORIDA.

ROTARY INTERNAL-COMBUSTION ENGINE.

1,228,072.

Specification of Letters Patent. Patented May 29, 1917.

Application filed June 30, 1916. Serial No. 106,917.

To all whom it may concern:

Be it known that I, JOHN M. SINER, a citizen of the United States, residing at Parish, in the county of Manatee and State 5 of Florida, have invented new and useful Improvements in Rotary Internal-Combustion Engines, of which the following is a specification.

This invention relates to rotary internal 10 combustion engines, the object in view being to produce a simple reliable and powerful engine of the class described which may be economically manufactured and maintained.

15 One of the chief objects of the invention is to provide a novel combination of rotor, rotor casing, expansion chamber, valve and charge compressing means, whereby the explosive mixture is highly compressed and 20 delivered to and contained by a hollow or tubular valve and quickly released into the expansion chamber by operating means controlled from the engine shaft, the compressed charge being exploded within a confined space between an abutment carried by 25 the rotor and a sliding abutment carried by the rotor casing.

With the above and other objects in view the invention consists in the novel construction, combination and arrangement herein 30 fully described, illustrated and claimed.

In the accompanying drawings

Figure 1 is a side elevation of an engine embodying the present invention, looking 35 toward the cam side thereof.

Fig. 2 is an elevation looking toward the opposite side of the engine, showing the charge compressing means, one cylinder of which is illustrated in section.

40 Fig. 3 is a vertical longitudinal section through the engine.

Fig. 4 is a vertical diametrical section through the same.

Fig. 5 is an enlarged circumferential 45 cross section extending through the sliding abutment and the valve chamber showing the oscillatory inlet valve in section.

Fig. 6 is a fragmentary sectional view 50 through the casing showing the cut-off spark plug and inlet valve.

Fig. 7 is a fragmentary vertical longitudinal section taken through the casing and a part of the rotor illustrating one of the inlet valves and one of the cut-offs.

55 The engine contemplated in this inven-

tion comprises, in the preferred embodiment thereof, a stationary cylindrical casing 1 having a broad extended base 2 adapting the same to be fixedly secured to a floor or other support.

60 The casing 1 as shown is provided at diametrically opposite places with outwardly extending and radially disposed housings 3 for a pair of slidable abutments or cut-offs 4. The casing 1 is also formed with a plurality of valve chambers 5 and a corresponding number of exhaust ports 6.

65 Mounted with the casing 1 is a rotor 7 which is shown as provided with a single abutment 8 having an eccentric face 9 which 70 coöperates with the inner extremities of the sliding cut-offs 4 for the purpose of pressing said cut-offs outwardly. The abutment also provides a working or pressure face 10 against which the expansive fluid acts, said 75 fluid being trapped or confined between the working face 10 of the abutment 8 and an opposing working face 11 of the adjacent cut-off 4.

70 Each of the cut-offs 4 is provided with a laterally extending pin 12 which works in a guide slot 13 disposed radially with respect to the centrally located engine shaft 14 on which the rotor 7 is fixed. Referring now to Fig. 1, the pin 12 of each cut-off 4 has attached thereto one end of a plunger rod 15 which works through guides 16 and 17 secured to or projecting from one of the disk shaped heads 18 of the casing 1. Each plunger rod 15 is pressed inwardly toward 80 the shaft 14 by means of a coiled expansion spring 19 which surrounds the rod 15 and is interposed between one of the guides 16 and a shoulder or collar 20 on said rod. At its inner end each rod 15 carries a roller 95 21 coöperating with a cut-off cam 22 having a fixed relation to the shaft 12. The cam 22 is so designed that it presses each of the abutments or cut-offs 4 outwardly to allow the abutment 8 of the rotor to pass by the 100 same.

85 The charge compressing means best illustrated in Fig. 2 is shown as comprising a pair of diametrically opposite cylinders 23 in each of which is mounted a reciprocating piston 24. The cylinders 23 are fixedly attached to the adjacent head 17' of the casing and the pistons 24 are connected by the usual rods 25 to a wrist pin 26 extending outwardly from a disk head 27 on one end 110

of the engine shaft 14 as shown in Fig. 4. The outer head 28 of the cylinders 23 provides a valve chamber 29 formed with an opening leading into the head of the cylinder and controlled by an intake valve 30 which is normally held seated by means of a spring 31 encircling the stem 32 of the valve. 33 designates one of the branches of an intake manifold connected to a suitable carbureter (not shown).

Each cylinder 23 has an outlet port 34 which is illustrated in Fig. 7 provided with a passage 35 leading to an inlet port 36 of an oscillatory inlet valve 37, said valve being provided in addition to the inlet port 36 with an outlet port 38 adapted to move into and out of register with a passage 39 which leads from the valve chamber 5 into the expansion chamber 40, said expansion chamber being of annular formation as shown in Fig. 3. The valve 37 is of tubular or hollow formation and is substantially cylindrical though slightly tapering from one end to the other to obtain a tight fit.

Each of the valves 37 is provided at one end with a stem 41 having fast thereon an arm 42 from which a link rod 43 extends to a rocker arm 44, pivotally mounted at 45 on the casing and co-operatively related to a valve operating plunger 46 which is slideable radially with respect to the engine shaft 14 through guides 47 and is pressed normally inward by means of a spring 48. The inner end of each rod 46 bears against and is actuated by a valve operating cam 49 having a fixed relation to the engine shaft 14, said cam being shown as provided with a cam projection 50 adapted to co-operate alternately with the plunger rods 46 for the purpose of alternately opening the oscillatory inlet valves 37. Each inlet valve 37 is provided at its other end with a stem 51 having fast thereon an arm 52 to which is attached one end of the valve closing spring 53 the other end of which is connected to a fixed point 54 on the adjacent head of the casing 1. The mechanism just described provides for a quick operation of the oscillatory valve 37 enabling the same to be quickly opened and closed for the purpose of releasing a compressed charge into the expansion chamber 40 and closes just prior to the formation of a spark in order to prevent back firing into said valve. The arrangement of the spark plug is illustrated in Fig. 6 in which it will be observed that the inlet end of the plug 55 is received in a firing cavity 56 formed on one of the side walls or heads 17' of the casing.

An ignition timer ring 57 having a fixed relation to the engine shaft 14 carries a contact point 58 which alternately touches a pair of oppositely arranged contacts 59 extending upwardly from a contact carrier or support 60. The timer 67 may be adjusted

so as to cause a spark at each plug 55 when the abutment 18 and the cut-off 11 assume the relative positions illustrated in Fig. 3.

In order to provide against leakage of compression the oscillatory valve 37 is held tightly to its seat by means of a spring 61 which acts to draw the valve 37 toward the smaller end of the valve chamber 50 indicated in Fig. 5. Each sliding abutment or cut-off 4 is provided in its inner end with a recess 62 in which is arranged a packing roller 63 which works in contact with the outer peripheral surface of the rotor 7 and the abutment 8. Passages 64 lead into the recess 62 behind the roller 63, the latter being thereby held by pressure of the expanded fluid in contact with the rotor. The abutment 8 is formed with grooves to receive one or more packing strips 65 which extend along the side faces of the abutment 8 and also across the periphery of the said abutment so as to contact with the heads and inner peripheral wall of the casing 1. Each cut-off 4 may be also provided with one or more packing strips 66.

Each cut-off 4 is preferably made wider than the expansion chamber 40 as illustrated in Figs. 5 and 6, the heads 17' being offset laterally as shown at 67 to form a cut-off chamber 68 which is sufficiently wider than the expansion chamber 40 to provide leak proof shoulders 69 both in front of and behind the cut-off. Other packing rings 70 are seated in grooves in the opposite sides of the rotor as shown in Fig. 4 and still other packing rings 71 are seated in grooves in the inner faces of the casing heads 17'. The rotor carried rings bear against the heads 17' and the rings 71 of the heads 17' against the opposite faces of the rotor.

From the foregoing description taken in connection with the accompanying drawings it will now be understood that each cut-off is moved outwardly by the cam 22 and in addition thereto the outward movement of each cut-off is insured by the eccentric face 9 of the abutment 8. The cut-offs are moved quickly inward by means of the springs 19 and pounding or slamming of the cut-offs is prevented by the cam 22 which has an abrupt face 72 which is inclined or rounded as shown at 73 thereby preventing the roller 21 from being driven violently in contact with the concentric portion of the cam as will be clearly seen in Fig. 1. It will also be understood that the charges compressed by the charge compressing cylinders are delivered to the oscillatory inlet valves which are of sufficient internal dimensions to each contain one charge of explosive mixture, and by reason of the valve operating means the latter are quickly opened and closed, the compressed charges being then trapped between the abutment 8 of the rotor and the adjacent cut-off 4.

Under the arrangement illustrated in the drawings, there will be 2 explosions or impulses for each rotation of the shaft 14 but it will of course be understood that the rotor 5 may be provided with one or more additional abutments 8 and also that one or more additional cut-offs 4 may be provided according to the size of the engine and the horse power to be produced. By providing 10 such additional abutments and cut-offs additional impulses or explosions will occur, it being further understood that the ignition timing device will be altered accordingly so as to produce a spark to ignite each charge 15 of mixture admitted to the expansion chamber.

What I claim is:—

1. In a rotary internal combustion engine, the combination of a stationary cylindrical 20 casing having radially extended cut-off housings, inlet valve chambers and exhaust ports; a central engine shaft, a rotor fast on said shaft having an abutment formed with an eccentric face and a working face substantially parallel to the working face of 25 the adjacent cut-off when in firing position; a plurality of radially movable cut-offs slideable in said housings between the inlet valve chambers and exhaust ports; oscillatory inlet 30 valves in said valve chambers, a plurality of charge compressors mounted on the stationary casing and driven from the engine shaft, intake valves for said compressors, and means for quickly opening and 35 closing said oscillatory inlet valves.

2. In a rotary internal combustion engine, the combination of a stationary cylindrical casing having radially extended cut-off 40 housings, inlet valve chambers and exhaust ports; a central engine shaft, a rotor fast on said shaft having an abutment formed with an eccentric face and a working face substantially parallel to the working face of the adjacent cut-off when in firing 45 position; a plurality of radially movable cut-offs slideable in said housings between the inlet valve chambers and exhaust ports; os-

cillatory inlet valves in said valve chambers, a plurality of charge compressors mounted on the stationary casing and driven from the engine shaft, intake valves for said compressors, cam mechanism for opening said inlet valves, and springs for quickly closing the same.

3. In a rotary internal combustion engine, 55 the combination of a stationary cylindrical casing having radially extended cut-off housings, inlet valve chambers and exhaust ports; a central engine shaft, a rotor fast on said shaft having an abutment formed 60 with an eccentric face and a working face substantially parallel to the working face of the adjacent cut-off when in firing position; a plurality of radially movable cut-offs slideable in said housings between the inlet valve 65 chambers and exhaust ports; oscillatory inlet valves in said valve chambers, and a plurality of charge compressors mounted on the stationary casing and driven from the engine shaft, said intake valves each having 70 ports only one of which at a time may register with its mating port in the casing.

4. In a rotary internal combustion engine, the combination of a stationary cylindrical 75 casing having radially extended cut-off housings, inlet valve chambers and exhaust ports; a central engine shaft, a rotor fast on said shaft having an abutment formed with an eccentric face and a working face substantially parallel to the working face of the adjacent cut-off when in firing position; a plurality of radially movable cut-offs slideable in 80 said housings between the inlet valve chambers and exhaust ports; oscillatory inlet valves in said valve chambers located between the compressors and the expansion chamber, a plurality of charge compressors mounted on the stationary casing and driven from the engine shaft, intake valves for said compressors, and means for quickly opening 85 and closing said inlet valves.

In testimony whereof I affix my signature.
JOHN M. SINER.
